UNITED STATES PATENT OFFICE.

RALPH A. LESLIE, OF CLEVELAND, OHIO, ASSIGNOR TO THE WINTON MOTOR CARRIAGE COMPANY, OF CLEVELAND, OHIO, A CORPORATION OF OHIO.

DESIGN FOR AN AUTOMOBILE-TONNEAU.

No. 37,763.

Specification for Design.

Patented Dec. 26, 1905.

Application filed October 23, 1905. Serial No. 284,116. Term of patent 14 years.

To all whom it may concern:

Be it known that I, RALPH A. LESLIE, a citizen of the United States, residing at Cleveland, in the county of Cuyahoga and State of Ohio, have invented a new, original, and ornamental Design for Automobile-Tonneaus, of which the following is a specification, reference being had to the accompanying drawings, forming a part thereof.

In the accompanying drawings, Figure 1 is

a side elevation of an automobile-tonneau embodying my new design. Fig. 2 is a rear view of the same.

I claim—

The ornamental design for an automobile-tonneau, as shown.

RALPH A. LESLIE.
